[57] CLAIM

The ornamental design for an automatic sheet feed device or the like, substantially as shown and described.

DESCRIPTION

FIG. 1 is a front perspective view of an automatic sheet feeding device or the like, showing my new design, the broken line showing of a printer or the like being environmental and forming no part of the claimed design.

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof.

FIG. 7 is a left side, rear perspective view thereof.

FIG. 1

FIG. 2

FIG. 3

FIG. 4

FIG. 5

FIG. 6

FIG. 7
